UNITED STATES PATENT OFFICE.

ANDREW J. STEPHENS, OF KANSAS CITY, MISSOURI

RUBBER STOP SIGN.

Application filed January 12, 1928. Serial No. 246,206.

The device forming the subject matter of this application is a rubber sign intended to be used on the surface of a highway in connection with traffic signals, the flexibility of the sign permitting it to bend when struck accidentally, to the end that the vehicle striking the sign may suffer no damage, and to the end that the sign itself may not be broken. One object of the invention is so to mount the sign that it will bend under impact, without cracking or tearing, at the place where it bends; and another object of the invention is to provide novel means for anchoring the sign in the highway.

It is within the province of the disclosure to improve generally and to enhance the utility of devices of that type to which the invention appertains.

With the above and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the drawings:—

Figure 1 shows in elevation, a device constructed in accordance with the invention;

Figure 2 is a top plan;

Figure 3 is an end elevation;

Figure 4 is a cross cut on the line 4—4 of Figure 1, with the pavement and the anchoring material as added details.

The body 1 of the sign is in the form of a plate of hard rubber which is flexible enough so that it can be bent and twisted repeatedly. The lower part 2 of the plate 1 is parallel-sided, but the upper part 3 of the plate is tapered in width toward its upper edge, to enhance its flexibility. The upper corners 4 of the plate 1 are rounded off to save the plate from damage. The lower part 2 of the plate 1 is mounted in a base made up of two blocks 5 of cushion stock rubber vulcanized or secured otherwise to opposite sides of the lower part of the plate 1. The blocks 5 are softer and more flexible than the plate 1, and, consequently, the plate 1 can be bent back and forth in the direction

of the arrows A in Figure 4, without causing the plate to crack where it bends (at 11) 55 at the upper edges of the blocks 5. The plate 1 carries any kind of an inscription 10, the word "Stop" being merely indicative of any desired marking. A recess 7 is formed in the highway 8 and the lower part 2 of 60 the plate, along with the base blocks 5, is placed in the recess, and then a quantity of anchoring material 9, which may be asphalt, is poured into the recess 7 on each side of the base of the sign. The anchoring material 9 coalesces, as shown at 12, through staggered openings 6 in the blocks 5 and in the lower part 2 of the plate 1, and this affords a very good anchorage for the article.

The body 1 and the base 5—5 of course 70 are not only flexible, but resilient, as well, so that they will resume the normal position and shape attributed to them in the drawings, after they have been bent or distorted, by impact or otherwise.

The letters which form the inscription shown at 10 preferably are made of a phosphorous compound mingled with carborundum, to provide a lettering which not only will be luminous, but which, also, will be 80 lighted up at night by the lamps of approaching automobiles.

I claim:—

1. A sign including an inscription plate of flexible rubber, and a flexible rubber base 85 in which the lower end of the plate is mounted, the base being more flexible than the plate, so that the base will yield when the plate bends, thereby to avoid a cracking of the plate at the upper edge of the base. 90

2. A sign constructed in accordance with claim 1 and further characterized by the fact that the plate tapers in thickness from the base toward the upper edge of the plate, thereby to enhance the resiliency of the 95 plate.

3. A sign constructed in accordance with claim 1 and further characterized by the fact that the base and the part of the plate that is therein are supplied with anchorage 100 openings.

In testimony that I claim the foregoing as my own, I have hereto affixed my signature.

ANDREW J. STEPHENS.
